UNITED STATES PATENT OFFICE.

FRANKLIN G. HOBART, OF BELOIT, WISCONSIN, ASSIGNOR TO FAIRBANKS, MORSE & COMPANY, OF CHICAGO, ILLINOIS, A CORPORATION OF ILLINOIS.

OIL-ENGINE-FEEDING DEVICE.

1,275,426.

Specification of Letters Patent. Patented Aug. 13, 1918.

Application filed May 19, 1915. Serial No. 39,045.

To all whom it may concern:

Be it known that I, FRANKLIN G. HOBART, a citizen of the United States, residing at Beloit, in the county of Rock and State of Wisconsin, have invented a certain new and useful Improvement in Oil-Engine-Feeding Devices, of which the following is a specification.

My invention relates to feeding devices for oil engines of the internal combustion class, and is applicable to either an engine of medium compression, as used in the so-called "semi-Diesel" type, or of higher compression as used in the true Diesel type. The general object of the invention is to procure a feeding device for this purpose which will be positive, simple, reliable and of economical manufacture. It may be stated in general in connection with my invention, that means is provided for forcibly injecting oil or other fuel into a combustion chamber of the engine, and the amount of fuel for each charge is regulated by means of a valve which controls the port leading to said pump. Timing mechanism for controlling said valve is provided, said timing mechanism being automatic in its operation and acting in accordance with the speed of the engine, the result being that I am able to control to a nicety the amount of fuel supplied to the combustion chamber, and at the same time the fuel is forcibly injected under the necessary pressure. Another object of my invention is to provide simple and efficient mechanism for priming the engine preliminary to starting the same. Another object is to provide a separate supply pump operated preferably from the main engine shaft for keeping the supply tank supplied with fuel. In the specific design selected to illustrate the invention, the fuel from the supply tank feeds to the pumping mechanism both by gravity and suction. Specific devices which enter into the mechanism will be referred to more in detail as the description proceeds.

I accomplish my objects by the construction illustrated in the accompanying drawings, in which—

Figure 1 is an elevation showing a general assembly view of an internal combustion engine equipped with mechanism embodying my invention.

Fig. 2 is a plan section taken through the center of the crank shaft and showing the

pumping mechanism and parts associated therewith.

Fig. 3 is a vertical section taken on the line 3—3, Fig. 2.

Fig. 4 is a vertical section showing the valves in the supply pump which furnishes fuel to the supply tank. The plane of section is indicated by the line 4—4, Fig. 2.

Fig. 5 is a side elevation of the timing cam and mechanism by which the same is governed. The plane of sight is indicated by the line 5—5, Fig. 2.

Fig. 6 is a detail showing the timing cam upon the main shaft.

Similar numerals refer to similar parts throughout the several views.

Now describing the particular design which I have chosen for the purpose of illustrating the invention, the cylinder 1 is mounted upon a base 2 supporting the main crank shaft 3, which is provided with a fly-wheel 4. Fig. 3 of the drawings illustrates an engine having but a single cylinder but it will be understood that the number of cylinders is immaterial.

The fuel supply tank 6 is kept supplied with fuel, the preferred mechanism for accomplishing this being hereinafter described. A pipe 7, which may be termed the fuel inlet pipe leads from tank 6 to a valve casing 8, as best shown in Fig. 2. A valve seat 9 is formed in said casing and this cooperates with the inlet valve 10 which controls the flow to the passage 11 leading to the main injection pump presently to be described. Valve 10 is urged toward closed position by a helical compression spring 12. Said valve is attached to a stem 13, which passes up through the casing 8. In case the fuel should creep up past the lower portion of stem 13 it passes off through a drain 14, best shown in Figs. 1 and 2. Stem 13 is operated by a push rod 15, provided at its lower end with a screw cap 16, which abuts the upper end of the valve stem. By screwing said cap up or down on rod 15 the position of valve 10 may be adjusted. A helical compression spring 17 which is interposed between cap 16 and the upper end of casing 8 tends to hold said push rod raised. Said rod is guided by the boss 19 formed on the housing 20.

The push rod 15 is operated by the timing cam 22, which is shown in section in Fig. 2, and separately in Fig. 6. This is loosely

5 mounted upon shaft 3 and is connected by pins or studs 23 to the sleeve 24 which forms part of the governor. The function of the governor is to rotate the cam 22, as
 10 a general thing in unison with shaft 3, but to produce in addition a temporary retardation or advancement relatively to the shaft to regulate or properly time the operation of the inlet valve 10 to thereby maintain the speed of the engine constant. The actual form of the governor is immaterial, and as
 15 centrifugal governors are well known it is sufficient for the present purpose to say that the governor in the design here shown, has a wheel 25 having its hub 26 fastened to the shaft. Governor weights 27 are pivotally mounted in the wheel upon studs 28 the free ends of the weights being connected by links 29 to said governor sleeve 24. Counter-balance
 20 springs 30 are connected in the known manner and the parts are so constructed and related that when the speed of the shaft exceeds normal the timing cam 22 will be rotated in one direction relatively to the shaft, and when the speed falls below normal it will be rotated in the opposite direction.

25 I will now describe the main injector pump and the means by which it is operated. The passage 11 which has been previously mentioned leads from the inlet valve chamber to the main pump chamber 32, as best shown in Figs. 2 and 3. Said pump chamber is located in the casing 33, which is preferably integral with the inlet valve casing 8, previously mentioned. A pipe 34 leads from the main pump chamber directly into the combustion chamber of the engine as shown in Figs. 1 and 3. This is in distinction from that type of engine in
 30 which the fuel is not introduced into the combustion chamber by the pump directly but is put into a receptacle from which it is blown into the combustion chamber by compressed air controlled in suitable manner. It is desirable to provide a check valve 35 at the outlet of chamber 32 to prevent back flow from the pipe 34. The plunger 37 of the main injector pump terminates in a head 38 which seats upon a coiled compression
 35 spring 39 and is normally held by it in contact with the slide 40 which reciprocates within the housing 20. A drain 41, shown in Figs. 1 and 4, leads from the inner end of the casing 33 to draw off any fluid that may pass the main plunger or any lubricating oil that may collect from the slide 40.

40 The slide 40 carries an anti-friction roller 42 mounted upon a shaft 43 fastened to the slide. Said roller is engaged and operated by the pumping cam 44 which is secured to shaft 3 by a key 45 or other suitable device. As the pumping cam is thus rigidly fastened to the shaft the main plunger 37 has a uniform program of operation, which

bears a constant ratio to the speed of the shaft. In other words, the plunger makes a complete round trip for every rotation of the shaft, and the position of the plunger is always the same for any given position of the shaft about its axis.

70 In the preferred construction here illustrated, the same shaft which serves to operate the injector pump and the inlet valve, serves also to operate the supply pump which keeps the supply tank 6 replenished. 75 This supply pump and its associated parts will now be described.

Secured to shaft 3 is an eccentric 47 which is encircled by a strap 48 which carries a pin 49 by which said strap is connected to 80 the inner end of plunger 50. Said plunger works in a casing 51 which terminates in a pump chamber 52 (see Figs. 2 and 4). Fuel is supplied to said pump chamber through a pipe 53 which leads from the main source 85 of fuel. An inlet check valve 54 is so arranged as to permit the fuel to enter chamber 52 but prevent it from returning through pipe 53. The fuel is led from chamber 52 to tank 6 through a pipe 55, 90 shown in Figs. 1 and 4. An outlet check valve 56 is so arranged as to permit the fuel to pass from chamber 52 to pipe 55 but prevent flow in the opposite direction.

95 While the form of the framework and housing supporting and inclosing certain of the previously described parts is immaterial, I have shown a stationary housing 57 which incloses the cams, and forms a support for the housing 20 and the casing 51, previously mentioned.

100 I have provided priming mechanism for introducing fuel into the combustion chamber of the engine by hand, preliminary to starting. In the form shown this priming mechanism consists of a lever 58 having a finger 59 entering a slot 60 in the side of the slide 40. The slot is long enough to permit the normal travel of the slide without interfering with said finger. The lever 110 is mounted upon a stationary pivot 61 supported in a quadrant 62. The lever is normally held in non-acting position by a latch 63 as shown in Fig. 3. When it is desired to inject fuel into the combustion chamber, 115 the lever is released and rotated back and forth by hand, thus reciprocating the plunger 37 of the main injector pump, and forcing fuel into the engine combustion chamber. When a sufficient amount of fuel has 120 thus been injected, the engine may be started by rotating the crank shaft in any suitable manner. A notch 64 is placed in quadrant 62 in such position that when the latch 63 is engaged therein it will hold the lever 125 58 in such position as to keep the roller 42 out of reach of the cam 44. Under such conditions the injector pump is held inop-

erative, with the result that the fuel supply to the combustion chamber will be shut off and the engine will come to rest.

While the engine, in starting, may be turned over manually or mechanically, as desired, I prefer to employ the air starting device shown at the top of Fig. 2. According to the design shown, a receiving chamber 70 is supplied with air under pressure through a duct 71 leading from any suitable compressor (not shown). Adjacent to chamber 70 is a chamber 72 connected by a duct 73 to the engine cylinder. The passage from chamber 70 to chamber 72 is controlled by a valve 74 mounted upon a stem 75 and cooperating with a valve seat 76. Stem 75 leads down through the housing 57 and is acted upon by a cam 78 which is here shown to be integral with the pumping cam 44 rigidly secured to the shaft 3. The valve is normally held open by a spring 80 against a stop 81. When compressed air is turned on through the duct 71, it closes valve 74 unless the cam 78 is in position to hold the valve open. The cam is so constructed as to control the admission of compressed air to the cylinder above the piston, admitting air at the beginning of the stroke and closing the valve before the end of the stroke and leaving the valve closed until the piston has again started on its downward stroke. During this period the engine operates as a compressed air engine, no fuel being introduced. While the engine is rotating under the influence of this compressed air the compressed air is shut off and the fuel oil feeding mechanism allowed to operate, thereby changing the engine from an air engine to an oil engine.

In operation, as soon as the engine has been started, and the fuel turned on in duct 7, the injector pump plunger 37 reciprocates under the action of the pumping cam 44 and forcibly injects fuel into the combustion chamber of the engine. The amount of fuel injected depends upon the timing of the inlet valve 10 which in turn is controlled by the timing cam 22, the latter being controlled by the engine governor. The governor, which is sensitive in its action, is called upon in my engine to operate only the inlet valve 10 which requires but little power, the power for operating the main injector pump and the storage supply pump being derived from parts rigidly fastened upon the engine shaft.

Having thus described my invention, what

I claim as new and desire to secure by Letters Patent is:—

1. In an internal combustion engine, the combination, with the engine cylinder, of a shaft rotating in proportion to the speed of the engine, a cam rigidly secured to said shaft, a pump having a plunger for introducing fuel into said cylinder, a slide operated by said cam and abutting the end of said plunger for forcing said plunger in a direction to send fuel to the cylinder, a spring engaging said plunger for retracting it and holding it in engagement with said slide, and manually operated means for reciprocating said slide independently of said cam.

2. In an internal combustion engine, the combination, with the engine cylinder, of a shaft rotating in proportion to the speed of the engine, a cam rigidly secured to said shaft, a pump having a plunger for introducing fuel into said cylinder, a slide having a longitudinal slot therein, said slide being operated by said cam and contacting said plunger for forcing the latter in a direction to deliver fuel to the engine cylinder, a spring for retracting said plunger and holding it in contact with the slide, and a lever having a finger projecting into said slot for engaging the slide and operating it independently of said cam, said slot being long enough to permit the slide to reciprocate under the action of the cam under normal conditions without engaging said finger.

3. In an internal combustion engine, the combination, with the engine cylinder, of a shaft rotating in proportion to the speed of the engine, a cam rigidly secured to said shaft, a pump having a plunger for introducing fuel into said cylinder, a slide having a longitudinal slot therein, said slide being operated by said cam and contacting said plunger for forcing the latter in a direction to deliver fuel to the engine cylinder, a spring for retracting said plunger and holding it in contact with the slide, and a lever having a finger projecting into said slot for engaging the slide and operating it independently of said cam, said slot being elongated to permit the cam to reciprocate the slide when said lever is in neutral position, said lever when in one acting position holding said slide retracted and out of the range of the cam.

In witness whereof, I have hereunto subscribed my name.

FRANKLIN G. HOBART.
